STREET TRAFFIC CONTROL SYSTEM WITH SELECTIVE AUTOMATIC TIME DIRECTION

Charles Adler, Jr., and Henry A. Barnes, Baltimore, Md.

Application November 7, 1957, Serial No. 695,057

4 Claims. (Cl. 340—42)

This invention relates to street traffic control systems, and, in particular, to an improvement in street traffic control systems which allows for unidirectional traffic movement on certain thoroughfares during predetermined times of the day.

It is an object of this invention to provide an auxiliary means for controlling street signals whereby the signals for certain main streets or thoroughfares are maintained in a condition for one-way traffic travel during certain periods of the day, and whereby the signals for the same streets or thoroughfares are maintained for two-way traffic during other periods of the day.

It is a further object of this invention to provide an auxiliary means of the above-described type which may be used in connection with any conventional main signal system which controls traffic indicators.

It is a still further object of this invention to provide a selective traffic control means in which provision is made for only changing the signals at a time when the traffic is in a condition for a change.

Still a further object of this invention is to provide an auxiliary system including means to inform the operators of vehicles approaching the selectively-controlled thoroughfare that the vehicle may travel across the thoroughfare, or that it may travel in only a selected direction along the thoroughfare, or that it may travel in any direction with respect to or along the thoroughfare.

Yet another object of this invention is to provide an auxiliary system which may be put in condition for controlling traffic along the thoroughfare by means of a single switch.

Other objects and the particular advantages of this invention will become apparent to those of ordinary skill in the art when the following description is considered in conjunction with the annexed drawings, wherein:

Figure 1 is a plan view of several intersections along a thoroughfare which has been equipped with signaling means in accordance with the provisions of this invention;

Figure 2 is a schematic diagram of the auxiliary control means and means for operating the same by this invention for accomplishing the objects above set forth;

Figure 3 is a schematic diagram of a push-button switch which may be used with the circuit of Figure 2 according to this invention; and

Figure 4 is an elevational view of a preferred type of accessory signal means which may be used in conjunction with conventional signal means in accordance with this invention.

Referring to Figure 1, a thoroughfare is indicated at 10 and, as is customary, this thoroughfare carries, at certain periods of the day, a heavy load of traffic, for instance, incoming to a central city, and at other periods of the day carries a heavy volume of traffic outgoing from that central city. During the time when the traffic volume is considerably lessened, traffic may move on the thoroughfare in either direction but at the peak periods, provision is made for one-way travel only on the thor-

2

oughfare. This invention provides a system completely automatic and selectively controlled so as to direct traffic in one single direction as required during the peak periods without, however, interfering with normal traffic control on intersecting streets or highways. An intersection of a side street 14 and the thoroughfare 10 is indicated at 11, and the intersection is provided with any customary signaling equipment utilizing at least separate stop and go indicators. For purposes of illustration, this equipment 12 is shown as provided with red, yellow and green indicators and directional indicators 13. These indicators comprise lamps in front of which are disposed colored glass faces, as is customary. One piece of equipment is provided on each of the four corners of the intersection. However, one or more units may be suspended over the intersection, as customary, for instance, at the point "X" without departing from the operation of the system of this invention.

Associated with the signals visible to traffic moving over the cross street 14 are automatic directional indicators having signal arrows 15 and 15' which will show drivers approaching the intersection on the cross street 14 when traffic is directional on the thoroughfare, and the direction of same.

Associated with the signals which face traffic moving on the thoroughfare 10 are directional indicators having arrows signals 16 and 16' whereby when a vehicle is traveling north or south, and the boulevard control is changed to one direction or another, these arrows will direct a driver, who is traveling against the single direction, to turn off of the thoroughfare to the right or left.

In the operation of the selective system, when the signals are operating normally, the arrows 15, 15', 16 and 16' will not be energized. When the peak load is traveling south on the boulevard 10, the automatic control acts to lock the red indication of signal means 12 on the NE corner of intersection 11. The red indication locks only during the red interval when traffic is moving across the thoroughfare and then holds red. The red does not come on suddenly, in the midst of a green boulevard period, as this would tend to cause sudden stops and rear-end collisions.

In the operation of an ordinary traffic control system, when both the north and south lanes of thoroughfare 10 are being utilized for two-way traffic so that the north-south indicators present green, the indicators for the cross street 14 are red on each side. When the green indicators are about to change, due to the normal automatic operation of the control system, the east-west signals will remain red, while the green signals go to the amber indication. Thereafter, when the north and south indicators change to red to permit cross-street travel, the east-west indicators change to green, and the north-south indicators remain red, while the east-west indicators, in their normal operation before another change, present amber to opposite sides of the thoroughfare. Thereafter, of course, the east-west indicators turn to red, and the north-south indicators return to green.

When the auxiliary control means is operative, as provided by this invention, the above pattern is not followed. For example, when the southbound traffic is presented with a green indication, all northbound traffic will be presented with a red indication and the directional indicators, with arrows 16 associated with the northbound indicators 12 on the NE corner, will indicate to any drivers who are moving in the northbound direction that they should turn to the right or left to leave the boulevard and at this time the indicators on the east-west cross street indicate red. When southbound traffic is presented with an amber indication, northbound traffic will still be presented with red indications, and east-west traffic will remain presented with red indica-

tions. When southbound traffic and northbound traffic are both presented with red indications, east-west traffic on the cross street 14 will be presented with green indications and the directional indicators, with the proper arrows 15', will indicate the direction of traffic on the thoroughfare 10. When southbound traffic and northbound traffic are both presented with red indications, and east-west traffic indications are about to be changed, in the normal operation of the indicators from green to red, the indicators will first show amber, and after east-west traffic indicators show red, then the southbound traffic indicator will again show green, but the northbound indicator still shows red.

When it is desired to have northbound traffic only on the thoroughfare 10, southbound traffic will be presented with a red indication and the directional indicators, with arrows 16', will inform an operator of a vehicle that a left or right turn must be made. The northbound traffic indicators will present a green indication, and a red indication will be presented to east-west traffic. In the normal operation of the indicators for permitting the passage of east-west traffic, there is presented, during the sequential operation, an amber indication to northbound traffic, while the red indication remains presented to south-bound traffic and a red indication remains presented to east-west traffic, but during a succeeding portion of the cycle, the latter indication is changed to green. Directional indicators, with the proper arrow 15, will show the direction of flow of traffic on the thoroughfare 10. When the change occurs, of course, both southbound and northbound traffic are presented with red indications.

By reason of this invention, it will be apparent that the normal conventional operation of traffic signals may be maintained. However, the flow of traffic may be directed during peak periods of a day. This control of direction of traffic on the boulevard 10 speeds the traffic up, yet safety is provided for in that no change in indications occurs when traffic is moving in both directions on the boulevard 10 during off-peak periods until a driver is given ample warning of a change in the indications. A red signal is on when the change is effected for traffic travel in one direction on the thoroughfare, and although a red indication is given to traffic traveling in the other direction along the thoroughfare, directional indicators will indicate to the driver faced with the continuous red signal that he should make a turn into the east-west street, as is most convenient.

Having thus generally set forth the operation desired of the traffic control system, attention will be directed to the circuit provided for carrying out the invention. The components of the system are shown in Figure 2 position for travel along thoroughfare 10 in the south direction. One of the pieces of signal equipment 12 is designated as SW, indicating that it is on the southwest corner of the intersection. Similarly, the designation NE indicates that the signal so designated is at the northeast corner. The directional indicators 13 are designated in the same way to show their respective locations.

In Figure 2, the numerals 119 and 120 are leads from a timing unit 100. This timing unit supplies current at a particular interval of the day to relay 51 through lead 119 and at another interval of the day it supplies current to relay 68 through lead 120. The timing unit may be a centrally located (remote) time clock which is responsible for signals during a certain period of the day, a traffic actuated central (remote) cycle computer, which functions to supply proper signals, or any other suitable timing means, located centrally or at individual intersections.

The details of construction of the timing unit form no part of this invention. The timing unit need only be responsible for sending a current through lead 119 or 120 at particular times of a day, and many timing de-

vices, including the types specifically set forth above, which will perform the necessary functions, are well known to those skilled in the art.

A basic structure used to perform the timing operation would comprise cam-operated switches geared to a clock mechanism and connected to a suitable source of power.

The circuit is connected to a main traffic control system which feeds current to particular connections within the circuit in the proper sequence.

The letters RC, AC and GC designate leads through which a signal is transmitted from a control network within the main system to the red, amber and green indications, respectively, shown in the form of lamps covered by colored glass, to the signal equipment on the northeast corner of the intersection. Of course, without the auxiliary control means provided by this invention the leads RC, AC and GC would be connected directly to red, amber and green signal lamps 101, 102 and 103, respectively. If the system is under normal operation, that is, two-way traffic on the main thoroughfare is maintained, then no current is being supplied to relay 51 through lead 119 or to relay 68 through lead 120. In this instance, when current is fed into red control lead RC, current flows through relay 61 from the connection of lead RC to that relay and to ground which is designated in the usual way. This current causes relay 61 to pull blades 62, 63 and 64, which are mechanically linked together, to the left in Figure 2. When current is no longer fed through lead RC, relay 61 opens. It will be noted, however, that when current is fed through lead RC, the red indication or lamp 101 is energized by virtue of the fact that lead 65 connects with lead RC and one side of the lamp 101. The other side of the lamp 101 is grounded.

During normal operation at any time when current is not being fed through lead RC, the blades 62, 63 and 64 of relay 61 are in the dotted line position shown in Figure 2. When the blades are in such position, current may be fed into lead AC and, as a result, amber lamp 102 is energized since one side of the lamp is grounded and the other side is connected through lead 66 to blade 63 and lead AC. Also, when the blades are in such position, current may be fed into lead GC, in which case it would pass through blade 64 and lead 68 to one side of green lamp 103, and through green lamp 103 to ground.

During the normal operation the directional indicator, with arrows 16 associated with the northeast corner signal equipment 12, would not be energized since they are connected to lead GC through blade 64 only when current is fed into red control lead RC, and, of course, when current is being fed into lead RC, no current is being fed into lead GC by the main control network.

The equipment 13 on the southwest corner functions in the same manner as that on the northeast corner. However, the contacts associated with relay 74 are responsible for current transmission to lamps 105, 106 and 107 and the directional indicators with arrows 16'. The relay 74 corresponds to relay 61, blades 75, 77 and 79 correspond to blades 62, 63 and 64, respectively, and the input leads RC', AC' and GC', connected to the main control system, correspond to leads RC, AC and GC, respectively.

Assume now that current is fed from timing unit 100 through cable 119 so that the system will be set to indicate one way traffic southbound on thoroughfare 10. The current fed through cable 119 flows through relay 51 to ground, thereby energizing that relay and causing blade 52 to move to the left. When blade 52 moves to the left it makes connection with a lead 57 extending from any suitable auxiliary current supply. Since the system would operate the same whether powered by alternating or direct current, lead 57 has been stated as generally connected to an auxiliary current supply. When

either A.C. or D.C. is used, one side of the supply may be grounded and the other side connected to lead 57.

When blade 52 connects with the current supply lead 57, relay 53 is energized by current flowing from the supply, through blade 52, lead 56 and relay 53 to ground. Energization of relay 53 causes blade 54 to move to the left and connect with lead 59, which connects with lamps 113 and 116. Since lead 55 connects blade 54 to the current supply lead 57, when blade 54 moves to the left, current flows through lead 55, blade 54 and lead 59 to one side of lamps 113 and 116 and through the lamps to ground. Lamp 113 illuminates an arrow 15' within directional indicator 13 on the northwest corner. This illuminated arrow points southward, and thus any motorist approaching intersection 11 traveling west is informed that he can not turn right. Lamp 116 illuminates an arrow 15' within directional indicator 13 on the southeast corner. This illuminated arrow also points southward and, hence, any motorist approaching intersection 11 traveling east is informed that he can not make a left-hand turn. In other words, the arrows indicate the direction of travel on thoroughfare 10.

It will be noted that lead 60 connects with lead 56 which, in turn, connects through blade 52 to the current-supply lead 57. Thus, when relay 51 is energized, lead 60 connects with a current supply. Because of this, and because blade 62 connects with lead 60 and one side of relay 61, when current is sent into lead RC from the main control system, and relay 61 pulls blades 62, 63 and 64 to the left, the blades lock in the left position. The path of flow is from lead 57, through blade 52, part of lead 56, lead 60, blade 62, lead 58 and relay 61 to ground. It will be appreciated that the blades associated with relay 61 only lock in position when relay 51 is energized, for only then does blade 52 complete the connection from an auxiliary current supply to relay 61. Moreover, the blades associated with relay 61 only lock in the left position after relay 51 is energized and after a current has been supplied to relay 61 through lead RC. Thus, the sequence of operation in normal conditions will not be interrupted such that red or stop lamp 101 is energized continuously until that lamp is energized during the normal sequence of signals received from the control network within the main traffic control system. Of course, lamp 101 is initially energized when a current is sent through lead RC because it is connected to lead RC through lead 65. It remains energized when blade 62 locks in its left-hand position because then lamp 101 receives current from the auxiliary current supply through lead 57, blade 52, part of lead 56, lead 60, blade 62, lead 58 and lead 65.

When the blades associated with relay 61 are locked in their left-hand position, blade 63 makes no connection with amber lamp 102 or any other load and, hence, any current entering through lead AC sees an open circuit. The blade 64, when locked in its left-hand position, does not connect with lead 68 but, instead, connects with lead 67 which, in turn, connects to one side of directional indicator 13 on the northeast corner. Thus, when current is supplied through lead GC for potentially energizing the green or go indicator during what would normally be the portion of the cycle during which a green indication appeared, it flows through blade 64, lead 67, and lamps 109 and 110 to ground but does not flow through lamp 103. Lamps 109 and 110, therefore, are energized and inform northbound traffic that it must turn to the right or left, but cannot proceed directly ahead. It is apparent that the energization of lamps 109 and 110 only occurs when it is permissible for that traffic to turn, that is, when the signal equipment 12 on the northeast corner would normally show a green signal. Because the circuit is connected with a main traffic control system supplying sequential control signals, this indication occurs when the indicating equipment on the southeast corner and that on the northwest corner both

show a red indication stopping traffic traveling on side street 14.

When the period during which current is supplied to lead 119 terminates, relay 51 is de-energized and the blades 62, 63 and 64 associated with relay 61 assume their dotted line positions. Of course, no irregular signal will be given that requires sudden action on the part of traffic because there would be no traffic facing the northeast corner, at such time, and, moreover, the signals would be given in accordance with the selection made by the main control system's control network.

It will be apparent that when current is fed to line 120, relay 68 is energized. Blade 69 moves to the left energizing relay 70, causing blade 71 to move to the left and connect lead 72 and lamps 114 and 115 to the auxiliary current supply through current supply lead 57'. Relay 74 would be locked in its left-hand position when current was fed to lead RC; the red control lead connected to the main control system's control network, because relay 74 is connected to lead RC' through lead 58' and because lead 73 connects through lead 56', and blade 69 to current supply lead 57'. Blades 75, 77 and 79 would move to their left positions and, as a result, one side of red lamp 105 would be connected to the current source through lead 76, lead 58', blade 75, lead 73, part of lead 56', blade 69 and lead 57'. At the same time, blade 77 would make no connection with a load, and blade 79 would connect with lead 81 so that the lamps 111 and 112, associated with directional indicator 16', would be energized when current was sent into lead GC' from the main control system's control network for potentially energizing green indicator lamp 107.

Of course, current would only be supplied through lead 120 when it was desired to maintain the signals on thoroughfare 10 in condition for one-way northbound traffic.

When current is not being sent through leads 119 or 120, connections are made between input leads RC, AC, GC, RC', AC' and GC' such that the main control system's control network operates the red, yellow and green lamps in a normal selective cycle.

As is apparent from the foregoing, passing current through lead 119 establishes connections for maintaining the signals at an intersection of the thoroughfare 10 in condition for one-way southbound traffic. The signals viewable by the southbound traffic are not affected by passage of current through lead 119, however. They are controlled by the main system's control network for proper traffic flow, and the main system signals are fed through leads RC', AC' and GC' directly to the lamps associated with each lead.

Similarly, passing current through lead 120 establishes connections for maintaining the signals at an intersection of the thoroughfare 10 in condition for one-way northbound traffic. The signals viewable by the northbound traffic are in this instance not affected by the auxiliary control means, but, instead, are controlled by the control network of the main system for proper traffic flow.

It should be understood that although the auxiliary control means has been described above in conjunction with indicators which incorporate lamps, the auxiliary control means may be used with any indicators which may be electrically energized. For example, electromagnetic sign indicators may be used. Moreover, for operation of the invention, amber indicators are not essential. Any traffic control-indicating equipment that has at least stop and go indicators will allow for utilization of the invention.

In Figure 4 is shown the preferred type of directional indicator for use with this invention. It comprises a housing 150 having one face which carries directional indicators in the form of arrows 151 and 152. Of course, these arrows are illuminated by lamps (not shown) disposed within the housing. Any suitable colored glass may be used as a cover for the arrow face; however, it is

preferable to use green, and in a conventional system, green should be used.

Although the auxiliary control means shown in Figure 2 has been applied hereabove to traffic control at one particular intersection, it is readily apparent that the means may be used to control traffic flow at a plurality of intersections. One auxiliary control means such as that shown in Figure 2 may be associated with each intersection and leads 119 and 120 may comprise cables extending along the thoroughfare for carrying the auxiliary control signals for setting the indicators at the intersections for one-way traffic. Such a system may be desired where there is sequential control of intersectional flow along the thoroughfare 10, that is, where like indicators disposed at a series of intersections along a main street and facing in one direction for a series of blocks are not controlled by a single signal from the control network of a main system, or such a system may be employed for the purpose of convenience.

It may be more convenient, however, to use a single auxiliary control means for effecting maintenance of one-way traffic operation, and such may be utilized by merely connecting the auxiliary control means to the main control network at the place where the main control network is located. The single auxiliary control means may be conveniently used where like indicators disposed at a series of intersections along a main street and facing in the same direction are controlled by a single control signal from the main network.

Referring again to Figure 2, it will be noted that a double-pole single-throw switch 153 has been provided for disconnecting the timing mechanism from cables 119 and 120. Of course, this switch provides a means for disconnecting the leads 119 and 120 from the timer during days when one-way traffic maintenance is not desirable, such as on Sundays or holidays.

Also, in Figure 2 is shown a switching means 121 connected to a current supply 154. The arm 125 of this switch connects with contacts 122, 123 and 124. When the arm engages contact 122 current is sent through lead 122' and through lead 119 and the auxiliary control means controlling northbound traffic establishes the proper indications for one-way southbound traffic on thoroughfare 10. When the arm engages contact 124, current is sent through lead 124' and lead 120, and the auxiliary control means controlling southbound traffic establishes the proper indications for one-way northbound traffic on thoroughfare 10. Contact 123 is a dead connection which arm 125 engages when the switching means is not being used for control. It is desirable to have a switching means, such as the illustrative one designated by the numeral 121, so that on particular occasions when heavy traffic is traveling along a particular thoroughfare to attend a particular event, such as an athletic contest, one-way traffic may be maintained. The switching means may be disposed in a central location or may be disposed near one of the pieces of indicating equipment.

In Figure 3, a push-button switching means, which may be used instead of switching means 121, is shown. The numeral 134 designates push-buttons which control switch blades 128 and 129 associated with the relays 130 and 131. The parts of the push-button switching means are shown in the position they occupy when an auxiliary control signal is being sent through lead 120. Blade 128 is connected through lead 155 to a current supply. Lead 132 connects with blade 128 and, as a result, when the blades are in the positions shown, current flows through lead 155, blade 128 and lead 132 to lead 120. This would cause energization of the auxiliary control means for establishing one-way northbound traffic on thoroughfare 10. If the stop button 134A were pushed, no contact would be made with leads 132 or 133 and, as a result, no auxiliary control signal would pass through the switch to leads 119 or 120. When the button 134D is pushed, blade 129 engages lead 133, and an auxiliary control signal is passed to lead 119 and the auxiliary control means for establish-

ing one-way southbound traffic on thoroughfare 10 is energized. Relays 130 and 131 have been provided for maintaining the blades 128 and 129 in the position set by the push-buttons.

When the blade 128 is set by push-button 134B in contact with lead 132, relay 131 is energized since current flows from an auxiliary current supply through lead 155, blade 128, part of lead 132, lead 135, and relay 131 to ground. Energization of relay 131 causes blade 128 to lock in the position shown. Pushing button 134A causes a break in the circuit as blade 140 is disengaged from lead 135, relay 131 is de-energized and blade 128 no longer engages lead 132 as spring 142 urges that blade away from contact.

When it is desired to send an auxiliary control signal through lead 119, push-button 134D is pushed such that blade 140¹ engages lead 141. Relay 130 is thus energized and blade 129 will lock in position since current flows from an auxiliary current supply, through lead 155, blade 129, part of lead 133, lead 133¹, blade 140, lead 136, and relay 130 to ground. Pushing button 134C removes the auxiliary signal from lead 119 as relay 130 is de-energized and the spring 142¹ causes blade 129 to no longer contact lead 133. Lamps 143 and 143¹ may be provided in parallel connection with relays 131 and 130 respectively if it is desired to have an indication of when an auxiliary signal is being sent through lead 119 or lead 120.

Referring again to Figure 1, it will be noted that the directional indicators 13 are disposed beneath the indicating equipment 12. It should be understood that this invention is not limited to such a disposition, and that the directional indicators may be disposed in any position near the indicating equipment, whether on the side of, on top of, or below the indicating equipment.

It should also be understood that particular relays having a particular number of contacts have been shown only for illustrative purposes, and that any suitable arrangement of relay contacts, and even of relays, may be used to control the indicator operation, as taught by this invention.

From a consideration of the foregoing description and annexed drawings, it will be apparent that the objects set forth above, and others which became apparent during consideration of this disclosure, have been successfully accomplished. Various modifications, other than those set forth herein, will become apparent to those of ordinary skill in the art and, for that reason, it is intended that this disclosure be interpreted as illustrative and not in a limiting sense when consideration is given to the appended claims.

50 We claim:

1. A traffic control system for use at an intersection of streets, said system comprising first and second traffic controllers facing in opposite directions on the same street and having electrically energizable stop and go indicators,
- 55 a main control means for sequentially supplying at least electrical stop and go signals to said indicators to alternately energize the indicators to control movement across the intersection along said same street, a first auxiliary control means electrically coupled to said main control means and to said first traffic controller and including stop indicator lock-in means for maintaining the stop indicator of said first traffic controller energized and go indicator lock-out means for maintaining the go indicator of said first traffic controller deenergized during a first extended period of a day in response to an electrical signal, second auxiliary control means electrically coupled to said main control means and said second traffic controller and including stop indicator lock-in means for maintaining the stop indicator of said second traffic controller energized and go indicator lock-out means for maintaining the go indicator of said second traffic controller de-energized during a second extended period of a day in response to an electrical signal, timing means electrically coupled to said first and second auxiliary control means for supplying electrical signals to said first and second auxiliary

control means during said first and second periods of said day respectively, means coupling said first auxiliary control means to said main control means for preventing energization of the stop indicator of said first traffic controller until an electrical stop signal is received from said main control means for energizing said stop indicator of said first traffic controller, means coupling said second auxiliary control means to said main control means for preventing energization of the stop indicator of said second traffic controller until an electrical stop signal is received from said main control means for energizing said stop indicator of said second traffic controller, a first directional traffic sign disposed to face in the same direction as said first traffic controller and having first energizable arrow indicators pointed in opposite directions, means coupling said first arrow indicators to said first auxiliary control means for energizing said first arrow indicators in response to electrical go signals normally fed to said first traffic controller go indicator from said main control means during said first period of the day, a second directional traffic sign disposed to face in the same direction as said second traffic controller and having second energizable arrow indicators pointed in opposite directions, and means coupling said second arrow indicators to said first auxiliary control means and said main traffic control means for energizing said second arrow indicators in response to electrical go signals normally fed to said second traffic controller go indicator from said main control means during said second period of the day, whereby one-way traffic can automatically be maintained on said same street in opposite directions during two different periods of a day.

2. A traffic control system as defined in claim 1 and further including a third directional traffic sign disposed to face in one direction on the street intersecting with said same street and having third energizable arrow indicators pointed in opposite directions, a fourth directional traffic sign disposed to face in the opposite direction to

5
10
15
20
25

said third directional traffic sign on the street intersecting with said same street and having fourth energizable arrow indicators pointed in opposite directions, means coupling one of said third arrow indicators and one of said fourth arrow indicators to said first auxiliary control means for causing said one third arrow indicator and said one fourth arrow indicator to be energized during said first period of a day, and means coupling another one of said third arrow indicators and another one of said fourth arrow indicators to said second auxiliary control means for causing the other third arrow indicator and the other fourth arrow indicator to be energized during said second period of a day whereby traffic approaching the intersection along the street intersecting with said same street will be informed as to the permissible direction of turn at the intersection during said first and second periods of said day.

3. A traffic control system as defined in claim 2 and further including power means, and switching means disposed near one of said traffic controllers and coupled to said power means and said first and second auxiliary control means for supplying an electrical signal to either of said auxiliary control means at periods of a day other than said first and second periods.

4. A traffic control system as defined in claim 3 where-in each of said auxiliary control means comprises an electrical network including a plurality of electromagnetic switching devices.
